(57) **CLAIM**

The ornamental design for a collapsible bag with wheeled cart, as shown and described.

DESCRIPTION

FIG. 1 is an isometric view of a collapsible bag with wheeled cart showing my new design;

FIG. 2 is a left side elevational view thereof;

FIG. 3 is a top plan view thereof;

FIG. 4 is a bottom plan view thereof;

FIG. 5 is a front elevational view thereof; and,

FIG. 6 is a rear elevational view thereof showing my design.

1 Claim, 3 Drawing Sheets

FIG.1

FIG.5
